(57) **CLAIM**

The ornamental design for a display screen with graphical user interface for viewing a topology of cloud computing, as shown and described.

DESCRIPTION

FIG. 1 is a front view of a display screen with graphical user interface for viewing a topology of cloud computing showing our new design; and,

FIG. 2 is a second embodiment thereof.

The broken line showing of a display screen and the remainder of the graphical user interface form no part of the claimed design.
